WILLIAM F. SCHONBEIN, OF PORTLAND, OREGON

COMBINATION AIR CLEANER AND HUMIDIFIER

Application filed December 23, 1929. Serial No. 416,167.

My invention has to do with devices for cleansing and adding moisture to warm air emanating from warm air furnaces. The invention is so designed that air previous to being warmed is brought into contact with running water in such a manner that particles of dust, dirt and other foreign matter are collected and carried away by that fluid. After the air has been cleansed, it passes to the heat chamber provided therefor in the furnace. During the interval of passage through the heat chamber, the moisture content of the air is increased by absorption of vapor originating in such chamber.

The invention is of exceedingly simple construction and may be very readily incorporated in a warm air furnace. The device for precleaning the air consists of a number of basins or pans arranged in stepped formation in the horizontal air intake pipe or shoe of the furnace. As is usually the practice, a vertical intake pipe conducts cold air to the shoe, which in turn provides passageway to the heat chamber. The pans are arranged in the shoe in horizontal planes one above the other, in the region of the junction of the vertical air pipe with such shoe. Each pan extends from side to side of the shoe, and each is set back a space toward the furnace with regard to the pan situated immediately below. Water is conducted to the pans, and from one to the other, commencing with the topmost and ending with the lowermost. The air passing through the vertical air intake, strikes the pans with considerable volume and in a series of rolling movements passes over the water in the pans; and as it does so the foreign matter in suspension is deposited in the water.

After the air has been cleansed it is conducted to the heat chamber, where it is warmed and additional moisture added thereto. The added moisture is absorbed from a supply provided by a humidor pan which is mounted in the heat chamber. This pan is so constructed that the water contained thereby is readily converted into vapor which is absorbed by the heated air. Of course, as the water evaporates it is re-

plenished by means of a float valve arrangement connected with a supply source.

From the foregoing it will be seen that this invention attains several objects, among which

One object is to provide a device for pre-cleaning warm air emanating from a warm air furnace.

Another object is to provide a device for supplying moisture to the pre-cleaned air emanating from a warm air furnace.

A further object is to provide a device as outlined, that is easy, simple and inexpensive to construct, and one that may be readily attached to a warm air furnace.

Other objects will be apparent upon reading the specification aided by the drawings, wherein

Figure 1 is a side elevation of a warm air furnace illustrating the installation of my invention therein;

Fig. 2 is a vertical cross section indicated by the section line 2-2 of Fig. 1;

Fig. 3 is a vertical cross section indicated by the section line 3-3 of Fig. 2;

Fig. 4 is a perspective of the invention;

Fig. 5 is a perspective of a cover used for enclosing the outer ends of the water pans;

Fig. 6 is a fragmentary detail showing the apertures provided for supporting the water pans;

Fig. 7 is a fragmentary detail partially in section, showing how the spacing bars are connected to the side plates;

Fig. 8 is a side elevation of a furnace, partly in section, and illustrates the manner in which the humidifier pan is supported in the heat chamber;

Fig. 9 is a side elevation in section of the humidor pan; and

Fig. 10 is a perspective of the plate designed to support the humidor pan.

Similar characters refer to similar parts throughout the several views.

In the drawings, this invention is shown in connection with a warm air furnace 1. Furnace 1 is provided with a horizontal air inlet pipe or shoe 2 with which communicates the vertical inlet 3. Shoe 2 communicates with an air heating chamber in the

95

100

furnace 1. The foregoing construction may vary somewhat according to the type of furnace, but as such construction is old and well known further description is deemed unnecessary. Shoe 2 has a passageway 4 communicating with passageway 4' of inlet 3 and with the heat chamber 4".

In order that the cleaning device may be incorporated in the shoe 2, the side 2' thereof is provided with a substantial opening, the location of which is concealed by the cover or side plate 6 of frame 5. Frame 5 is composed of two spaced side members or plates 6 and 7 respectively, which are held apart by the spacing bars 8. Bars 8 have threads run on each end upon which are threaded two nuts, 8' and 8" respectively, which are positioned one on one side of a plate and one on the other. Plate 6 is here shown as being rectangular in outline to provide a cover for the aperture in side 2'. Plate 7, of course, should be smaller than 6 in order that it may pass through such aperture, and it may be given the outline suggested in the drawings, wherein the portion 9 of the upper edge thereof is inclined. To allow plate 7 to rest at a proper height with regard to plate 6, it is provided with adjustable legs in the form of slotted plates 10 which are positionable along the bolt 12.

The plates 6 and 7 are provided with a like number of rectangular apertures 13. These are arranged in horizontal planes, one above the other, and are set back one over the other. These apertures are the supporting means for the pans 14, 15, 16, 17 and 18. The number of these pans, of course, is determined by the size of shoe 2. In this instance there are five, and they appear, through arrangement of apertures 13, as a series of steps. The pans extend through the apertures 13 in the plates 6 and 7, and the outer end of each projects substantially from the plate 6. The projecting ends of the pans are each provided with a removable cover 19 to prevent dirt from entering the pans from the outside.

It is proposed to provide a continuous flow of water back and forth through the pans, commencing with the uppermost and ending with the lowermost, the water running from each pan to the next immediately below. Each pan has an outlet 20 whereby water may flow from it to the pan below. In order that the water will flow from one end to the other of each pan as it flows from the topmost to the lowermost, each has a partition or deflector plate 21 which provides a channel 22 commencing at the outer end of the pan, extending to the inner end and returning to the outer end where it terminates in an outlet 20. Outlet 20 of the lowermost pan is of course, connected with a conduit designed to carry the water away. The pans are so supported within the frame 5 that they

may be removed at any time it is so desired. Water is supplied to the pans by means of the pipe 23 which has a control valve 24. As will be seen in Fig. 4, one end of each pan projects from plate 6. This will allow inspection of the individual pans.

In the foregoing construction it will be seen that the pans are arranged across the passageway 4 just below the passageway 4'. Cold air traveling to the furnace descends the passageway 4' with considerable force, and when it comes to the area occupied by the pans, a substantial portion thereof comes into contact with the water and the particles of foreign matter are deposited therein. After the air has been cleansed it is conducted to the heat chamber 4" where the temperature thereof is raised for heating purposes.

Prior to emerging from the heat chamber, moisture is added thereto, this is provided in the form of vapor originating from a humidor pan located within the heat chamber. The humidor pan 25 is in the upper portion of the heat chamber. Pan 25 is an elongated container provided with parallel ends and parallel sides and a bottom having a substantial portion 26 disposed at an inclination. The water in pan 25, as a rule does not completely cover the inclined bottom portion 26 as shown in Fig. 8. This allows the water to evaporate rapidly. The depth of the water is automatically controlled by float valve 27, operated by the float 28. Valve 27 may be of any desired type suitable for this purpose. Pan 25 projects into chamber 4" through an opening provided in wall 29 of furnace 1. A supporting plate 30 is secured about such opening. An opening 31 is provided in plate 30 which is occupied by the outer end portion of the pan 25. For the purpose of supporting the pan, plate 30 is provided with lugs 32, one each side of the opening 31. The pan 25 is secured to lugs 32 by means of pins 33 which serve also as hinges for the cover 34. The inner end of the pan is supported by rod 35 which passes through the tongue 36. Complete passage of the rod 35 is prevented by its head 37 which bears against the tongue. The outer end of rod 35 is threaded and extends through wall 29 of the furnace. A thumb nut 38 is threaded thereto and bears against the outer surface of the furnace wall. Threading and unthreading nut 38 will raise and lower the inner end of pan 25. When the inner end of the pan 25 is lowered the water therein will be enabled to cover the entire inner surface of the inclined bottom portion 26. A fluid supply pipe 39 is connected between valve 27 and T 40, to which is likewise connected the pipe 23. T 40 is connected to a supply source.

From the foregoing description it will be seen that this invention is admirably suited for the purpose for which it is intended. Its construction being such that it may very

readily be installed in furnaces that are in actual use without the necessity of making any material alterations in such furnaces, and when so installed it requires practically no attention.

Having described my invention, what I claim is:—

openings arranged in stepped relation, a series of liquid receiving pans extending through the respective openings and supported in said housing, one end of each pan extending outside said side wall, and communicating means between the extended ends of the successive pans. 70

WILLIAM F. SCHONBEIN.

75

1. A device of the character set forth, comprising a pair of spaced side plates, said plates having a plurality of corresponding apertures, elongated pans projecting through corresponding apertures, said apertures being so designed that said pans are arranged in stepped formation in horizontal planes one above the other, and said pans being constructed to allow a continuous flow of water from one to the other commencing with the uppermost. 15

2. A humidifier for warm air furnaces, comprising an elongated pan having the major portion thereof projecting into the heat chamber of such furnace, a plate secured to the wall of said furnace, lugs projecting from said plate providing a pivotal support for said pan, the bottom of said pan having a substantial portion arranged at an inclination to provide a shallow inner end, a tongue at the inner end of said pan, a rod projecting from said tongue and extending through the wall of said furnace, including a nut threaded thereto exterior of the furnace, a float valve in said pan, and a fluid supply pipe connected to said valve. 25

3. In combination with an air duct having a series of openings in a side wall thereof, said openings being staggered with respect to each other, an open top pan fitting into each opening, a support for each pan within the duct on which the pans are slideable, each said pan extending outside said side wall and each having a closure portion at its top for closing the opening, there being an opening in each closure portion for the introduction of water to the pans outside the wall of the duct, a pipe depending from each pan outside the duct each overhanging the opening of a pan next below, and a source of water supply overhanging and for discharging water into the uppermost of said pans. 40

4. In combination with an air duct, including a vertical cold air inlet pipe, and a horizontal cold air shoe communicating at its outer end with this lower end of the vertical pipe and at its inner end with a warm air furnace; of an air cleaning device arranged in the duct, at the juncture of the vertical and horizontal pipes, said air cleaning device including a series of liquid receiving pans arranged in stepped relation, said pans extending beyond one side wall of the duct and communicating means between the extended ends of the successive pans. 45

5. A cold air duct for furnaces including substantially a housing having one side wall thereof provided with a series of spaced
